[57]

ABSTRACT

Extended casing method and apparatus for completing an underwater well whereby complete and continuous pressure control is maintained at the surface drilling platform. A conductor casing is installed in the floor of a body of water with a casing head and riser attached near the floor. Other casing is installed and supported at the water floor by hanger heads and having other risers extending upwardly therefrom. Pressure control equipment is installed at the upper end of one of the risers. A tubing head designed to pass through the pressure control equipment and riser to which it is attached may be lowered to the innermost hanger-head and remotely latched thereto. Orientation apparatus may be lowered into the tubing head and attached thereto. A tubing hanger and tubing may be lowered through the pressure control equipment and latched to the tubing head in an annular position determined by the orientation apparatus. The tubing is plugged, the riser and control equipment removed and a Christmas tree assembly attached to the wellhead in fluidtight flow communication with the tubing string.

UNDERWATER WELL COMPLETION METHOD AND APPARATUS

CROSS-REFERENCE TO RELATED APPLICATION

This is a continuation of application Ser. No. 76,664 filed Sept. 30, 1970 now abandoned.

This application is related to and concerns an improvement on the invention disclosed in copending application Ser. No. 792,912 filed on Jan. 22, 1969 now abandoned and in application Ser. No. 103,839 filed on Jan. 4, 1971 as a streamline continuation of co-pending application Ser. No. 792,912, both assigned to the assignee of the present application.

BACKGROUND OF THE INVENTION

1. Field of the Invention

This invention concerns underwater drilling of oil and gas wells. Specifically, it pertains to methods and apparatus used in underwater extended casing operations.

2. Description of the Prior Art

Increased activity in offshore drilling has resulted in a continuous search for better methods and apparatus in this area. To cope with the unique problems associated with underwater drilling, various extended casing methods have been developed. Basically, extended casing methods have a well conductor anchored to the sea floor which provides support for a special underwater wellhead. The wellhead, in turn, supports a multiple number of casing strings and their respective casing hangers. The drilling platform is thus relieved of much of the structural support responsibilities of other methods. After drilling is completed, the well may be permanently abandoned, temporarily abandoned or immediately completed. For any of these options, the completion equipment may be installed at the sea floor, leaving the drilling platform free for relocation and freeing the underwater wellhead from the hazards of ocean going traffic and structural support problems. One such extended casing method is fully described in U.S. Pat. No. 3,421,580 issued on Jan. 14, 1969 to J. H. Fowler et al.

In the extended casing methods of the prior art, one or more intermediate casing strings, in addition to the conductor casing and the innermost production casing string, are usually supported in the wellhead. Casing extensions or risers are attached to these strings as they are lowered into place and landed. The extensions are connected at the surface to a blowout preventer for pressure control and also serve as a return for cement circulation. In the past it has been necessary to remove all casing extensions, except possibly the outer conductor riser, for installation of the tubing head with the collector connector flange for making connection with the underwater tree, the tubing hanger, and the tubing strings. This requires removal of the surface blowout prevention equipment. In some cases for safety precautions, a bridge plug is set in the production casing prior to removal of the production casing riser. The tubing head is attached to the production casing hanger head and a high pressure riser extended back to the surface for re-attachment of the preventer equipment. The bridge plug is then drilled out or otherwise and the well is then ready to receive tubing. These operations require additional equipment, time and consequently expenses.

Some methods have utilized underwater blowout preventers installed near the underwater wellhead. However, such preventers are very expensive and more complex to operate than the conventional above water type.

SUMMARY OF THE INVENTION

The present invention concerns a method of completing an underwater well comprising the steps of: locating drilling means at an underwater well site; installing conductor casing in the floor of a body of water with a casing head and riser attached thereto at a point near the floor, the conductor riser extending upwardly to the drilling means; drilling holes for, suspending 10 within the conductor casing and cementing in place other casing, each of the other casing being suspended by hanger means above which other risers, extending upwardly to the drilling means, are connected; attaching blowout pressure control equipment to the top of 15 at least one of the other risers; running a tubing head through the pressure control equipment and its riser for attachment to the innermost hanger-head; running a tubing hanger and at least one tubing string, through 20 the control equipment and the riser to which it is attached, into the innermost casing; suspending and 25 latching the tubing hanger and tubing string in the tubing head; and removing the pressure control equipment and the other risers.

This method provides complete and continuous pressure control throughout completion by providing apparatus whereby the tubing head, tubing hanger and tubing string may be lowered through blowout preventers and a riser to their support positions. After latching the tubing hanger and tubing string in place the tubing is 30 plugged and the riser and pressure control equipment are removed for installation of the Christmas tree assembly.

BRIEF DESCRIPTION OF THE DRAWINGS

Other objects and advantages of the invention will become apparent from the description which follows when taken in conjunction with the drawing in which:

FIGS. 1 through 6 are step by step sectional elevation views of an underwater well showing a method and apparatus for completing a dual tubing string well according to a previously developed method,

FIGS. 7 through 10 are step by step sectional elevation views of an underwater well showing a method and apparatus for tubingless completion of a well according to a previously developed method,

FIGS. 11 through 14 are step by step sectional elevation views of an underwater well showing still another method and apparatus for completing a dual tubing string well according to a preferred and improved embodiment of the invention, and

FIGS. 15 and 16 illustrate an exemplary environment in which the present invention may operate.

DESCRIPTION OF THE PREFERRED EMBODIMENTS

The present invention is an extended casing completion system for use when drilling from a bottom supported rig with blowout prevention control equipment at the surface. Several options on the method of completion are available, including:

1. Easy permanent abandonment,
2. Temporary abandonment,

3. Completion by extension of casing, risers to a platform,

4. Casing-tubing sub-surface completion with optional diver support or fully remote operation, and

5. Tubingless sub-surface completion with optional diver support or fully remote operation.

The apparatus of the present invention permits installation of one or more tubing strings through blowout prevention control equipment and extended risers, eliminating the necessity of removing the risers and blowout preventers when preparing the well for completion. Because all operations are conducted through the risers and blowout preventers, well pressure control is continuous and remote guidance systems are not necessary when temporarily abandoning the well or preparing it for completion. A guide base may not be installed until a decision is made to complete the well. This allows a selection at that time of either fully remote Christmas tree installation or diver support Christmas tree installation.

Referring now to FIGS. 15 and 16, there is illustrated a bottom supported well drilling and completion apparatus which is entirely conventional except for the tubing hanger-head which is shown in more detail in the other figures. FIG. 15 shows the upper portion of a bottom supported rig 1 with blowout prevention control equipment 2 above the water surface 4 and surmounting the upper end of risers 12, 43, 53 and 63 extending from the rig 1 to the well head 5 at the mudline 3.

FIG. 16, in larger scale, shows a downward extension of risers 12, 43, 53, 63 from the rig 1 to the mudline 3 beneath the water surface 4, and also shows the well head 5 supporting progressively smaller concentric casing strings 10, 40, 50 and 60 in the well bore. Each sting of casing is cemented in the well bore from the lower ends of the casing strings to a level thereabove as indicated at 6, 7, 8, and 9. Production casing 60 extends from the rig 1 through the ocean floor 3 and water 4 to the production zone 14.

Referring first to FIGS. 1 through 6, a step by step description of casing-tubing sub-surface completion, according to a preferred embodiment of the invention, will be given. The system described will be a $30 \times 16 \times 10 \frac{3}{4} \times 7$ inch casing program with two $2 \frac{3}{8}$ inch tubing strings. However, it is to be understood that the size and number of casing and tubing may vary without departing from the principles of the invention.

First, a 30 inch conductor casing 10, casing head 11, and conductor riser 12 are lowered from the drilling platform 1 and driven or jetted into the sea floor 1 until casing head 11 rests near the floor. If bottom conditions require it, a hole may be drilled for conductor casing 10. Casing head 11 is provided with an upwardly facing stop shoulder 13 for locating the surface casing.

Riser 12 is connected to casing head 11 by an easily disengageable connection 14. One type of easily disengageable joint is shown in FIG. 1A. This type of joint, which we refer to as a breech block joint, reduces drilling costs by eliminating on-site welding, permitting easy recovery of casing risers and reducing rig time during making, running and recovering casing risers. The joint comprises a female member 20 and a male member 30. Segmented threads 21 of a square nonlead profile spaced 30° apart are milled in the female member for engagement with corresponding segmented threads 31 on the male member. Smooth milled out areas 22, 32 are provided between the thread segments

21, 31. For descriptive purposes the thread segments 21, 31 are referred to as lands and milled out areas 22, 32 as grooves. Engagement is accomplished by inserting the lands of the male member 30 in the grooves of the female member 20, then rotating the male member 30 degrees in either direction until the lands of each member are in full engagement. A positional stop 33 on the male member cooperates with lugs 35 around the female member to limit rotation to thirty degrees. A 10 pivotable anti-rotation latch 34 may be provided to engage the opposite side of lugs 35 preventing disengagement of the joint.

After the 30 inch conductor casing is set, a hole is drilled for 16 inch surface casing 40, which is lowered into place with surface casing head 41, back-off joint 42 and surface casing riser 43 attached thereto. Back-off joint 42 and head 41 may be connected by a breech block joint 46 similar to that shown in FIG. 1A. Landing lugs 44 are provided on surface casing head 41 cooperating with stop shoulder 13 to locate surface casing 40. The surface casing 40 is then cemented in place. The remaining strings will be supported by the cement around surface casing 40. Casing head 41 is provided with internal annular recesses to receive hanging latches for the next string.

Next a hole is drilled for the $10 \frac{3}{4}$ inch intermediate casing string 50 which is lowered into the hole attached to hanger-head 51, back-off joint 52, and riser 53 and cemented in place. Hanger-head 51 and back-off joint 52 are connected with another breech block connection 54. Hanger-head 51 is provided with spring biased latches 55 which support the casing string 50 within the well. As the latches 55 engage recesses 45, a locking rib 56 on the hanger-head body locks them into positive engagement. Hanger-head 51 may be provided with internal circulation ducts 57 or the latches 55 may be fluted for cement circulation. Internal latch recess 58 and circulation ducts 59 may be provided for ducting around the next hanger-head. Blowout prevention control equipment is attached to the top of riser 53 at the drilling platform 1.

Next the hole for production casing string 60 is drilled and the production string is landed and cemented in place attached to hanger-head 61, back-off joint 62 and riser 63. Production string hanger-head 61 is similar to hanger-head 51 having spring latches 65, a locking rib 66 and if necessary flow ducts 67. However, it has no internal latch recesses and it is connected to back-off joint 62 by a left hand thread connection 64 rather than a breech block joint. Immediately above the connection 64 two internal tubing hanger hold down recesses 68 are cut. An external key 69 provides orientation for a subsequently installed tubing hanger. Therefore, the production string 60 must be properly oriented while running in place.

The aforementioned drilling is done through the blowout prevention equipment at the drilling platform. At this stage of the drilling, the wellhead equipment would be as shown in FIG. 1. At this time the production string riser 63 is removed by rotating the riser joint and back-off joint 62 to the right.

Referring specifically now to FIG. 2, an orientation sleeve 70 connected by a J-slot arrangement 76 to running tool 71 and running string 72 is run through $10 \frac{3}{4}$ inch riser 53. A longitudinal slot at the base of sleeve 70 engages hanger-head key 69 and the sleeve comes to rest against hanger-head shoulder 73. An orientation

bushing 74 is affixed to the interior of sleeve 70 for automatic guidance of a tubing hanger which is to be installed. It has a dual 180° ramp 75 and a vertical slot 76 communicating with the ramp at its lowermost intersection. Tool 71 is then disconnected from orientation sleeve 70 and removed.

Referring now to FIG. 3, a tubing hanger 80, tubing 90, 91 and annulus access nipple 92 are installed along with test tool 93. Tubing hanger 80 is provided with three vertical bores 81, 82 (one not shown) communicating with annulus access nipple 92 and tubing strings 90, 91. Long tubing handling string 94 is connected to hanger 80 by a handling nipple (not shown) similar to handling nipple 95 connected to short string handling string 79. Both nipples pass through test tool 93. However, nipple 95 is screwed into a landing nipple 96 whereas the long string handling nipple is screwed directly in hanger 80. Both tubing strings 90, 91 are lowered together. However, short string 91 is displaced upwardly a slight amount from the position shown in FIG. 3.

Hanger 80 is provided with a longitudinal key 83 which rides on orientation bushing ramp 75 until it engages orientation slot 76 orienting the tubing hanger 80. The tubing hanger comes to rest on the upper shoulder 85 hanger-head 61. A hold down latch 86 and locking sleeve 87 are mounted in a skirt portion of hanger 80 near its base. In the running position the latch 86 is retracted and locking sleeve 87 is held up against the body of hanger 80 by engagement with landing nipple 96. When the hanger 80 is landed, short tubing string 91 and landing nipple 96 are allowed to move downwardly to the position shown in FIG. 3, where it is supported by shoulder 88, causing locking sleeve 87 to force hold down latch 86 into engagement with hanger-head hold down recesses 68. Up to this point handling nipple 95 and landing nipple 96 are fully made up so that the upper edge of landing nipple 96 is abutting downwardly facing shoulder 97 on handling nipple 95. By rotating handling nipple 95 to the right these shoulders are separated allowing a snap ring 89 in hanger 80 to spring out engaging the upper edge of landing nipple 96 and holding the short tubing string 91 down. At this point all wellhead components appear as shown in FIG. 3.

Next the tubing hanger seals would be tested by pressurizing through short tubing string 91. Pressure would then be applied below the tubing hanger 80 and through annulus access nipple 92 and tubing 90. Testing tool 93 is provided with a vertical port 98 and a horizontal port 99 which communicates with long tubing string 90 through a port in the handling nipple (not shown) attached to handling string 94. Should any of the seals around hanger 80 and landing nipple 96 leak it will be detected in riser 53.

Next, the downhole tubing packer is set, usually by hydraulic means, a back pressure valve is installed in long string 90 and the packer pressure tested. Pressure is applied through short string 91. If the packer leaks the test fluid passes through annulus access nipple 92 and through test tool ports 98, 99 into handling string 94 for detection.

If all tests are positive, the tubing handling strings 94, 79, their respective handling nipples, and test tool 93 are removed from the hole by rotating the handling strings to the right. The orientation sleeve 70 and orientation bushing 74 are removed using the running tool

71. The tubing strings 90, 91 and annulus access nipple 92 are plugged. It will be noticed that throughout running and setting of the tubing hanger and tubing strings complete pressure control is maintained at the surface by blow-out prevention equipment connected to 10 % inch riser 53.

Next, the pressure control equipment, 10 % inch riser 53 and 16 inch riser 43 are removed by 30° rotation to the right for disengagement of breech block connections 54 and 46. At this stage, the wellhead will appear as shown in FIGS. 4 with conductor extension 12 being the only remaining riser.

Referring now to FIG. 5, a tubular Christmas tree adapter 100 is run on drill pipe 120 using a combination running testing tool 130. The external midportion of adapter 100 is provided with the male part of a breech block connection 101 for engagement with the female part of the connection 101 in the 10 1/4 inch head 51. Rotatably connected by ball bearings 102 to the lower part of adapter 100 is an annular packoff assembly comprising a resilient seal member 104 sandwiched between upper and lower retainer members 103, 105. Lower retainer 105 is stopped against hanger-head shoulder 106 and as the breech block connection 101 is engaged upper retainer ring 103 presses against seal member 104 causing it to sealingly engage the walls of hanger-heads 51 and 61. A port 131 connects the bore 132 of tool 130 with the annular space between adapter 100 and tubing hanger 80. This space is sealed at 133, 134 by O-rings, allowing adapter seals 104, 108, 109 and tubing hanger seals 110 to be tested.

Christmas tree adapter 100 has an upper flange member 111 and internal connection threads 112 to which tool 130 is connected. Christmas tree adapter 100 also has stop lugs 113 which cooperate with stop lugs 114 on the top of hanger-head 51 when the breech-block connection is made to stop rotation at full engagement. To prevent disengagement, a locking ring 115 with depending lugs 116, is mounted around adapter 100 and held upwardly thereon as shown by radial pins 117 which ride in an L-slot 135 in sleeve skirt 136 of tool 130. A shear pin 137 is sheared on further right hand rotation of tool 130. This allows skirt 136 to rotate to a position where pins 117 drop out of the L-slot allowing the locking ring 115 to drop downwardly so that its lugs 116 fall between the back of adapter lugs 113 and the next closest hanger-head lug 114. This prevents rotation of adapter 100 in either direction thus locking it in position. Further rotation of tool 130, to the right, releases it for removal from the well.

If it is decided to temporarily abandon the well, rather than immediately complete it, a corrosion cap (not shown) may be run on drill pipe using a J-type running tool. It would be connected to the internal threads 112 of tubing head adapter 100. The corrosion cap could be provided with a port for spotting oil within the wellhead to prevent corrosion. This port would, of course, be plugged after the oil was injected. After installation of the corrosion cap, conductor riser 12 would be removed by rotating 30° to the right. A corrosion cap top could be installed by a diver and the well could be temporarily abandoned.

Alternatively, if it is desired to immediately complete the well, rather than install a corrosion cap, the Christmas tree would be installed. To do this, conductor riser 12 would be removed. Now referring also to FIG. 6, a small guide base 140 with two guide posts 141 would

be clamped around the lower part of adapter 100 or hanger-head 51 by a diver. The guide base would be oriented by a tool with two pins adapted to engage tubing receiving pockets 118, 119.

Next, Christmas tree 150 would be lowered to the wellhead. It would be provided with guide arms 151 and bell bottom sleeves 152 which would engage guide posts 141 to assist a diver in installing the tree 150. The base of tree 150 carries three long nipples 153, 154, the one for tubing 90 not shown, which sealingly engage the corresponding receiving sockets 118, 119, the one for tubing 90 not shown, in hanger 80. The base of tree 150 would come to rest against the upper face of adapter 100. An annular seal ring 155 would be provided at the joint. The tree 150 is then clamped to Christmas tree adapter 100 by a standard type clamp 160. A remote hydraulic connector could be used as an option eliminating the need for a diver to torque up clamp bolts. Thus, as shown in FIG. 6, the well is ready for production.

Should it be necessary at a future date to perform workover operations, tubing strings 90, 91 would be plugged and the Christmas tree 150 removed. Then a workover riser with a built in orientation sleeve and bushing similar to sleeve 70 and bushing 74 in FIGS. 2 and 3 would be attached to tree adapter 100. The orientation bushing would have a slot to engage key 83 of tubing hanger 80. In this manner, after the tubing hanger 80 is re-installed, following workover operations, it is landed in the same position as it was before workover operations.

If a tubingless sub-surface completion is desired, instead of a casing-tubing sub-surface completion, a somewhat different procedure is followed. However, with reference to FIG. 7, the first steps are the same as in the casing-tubing sub-surface completion just described. A 30 inch conductor casing 210, casing head 211, and conductor riser 212 connected by breech-block joint 214 are installed. A 16 inch surface casing 240, casing head 241, back-off joint 242, and riser 243 are installed. Next, the 10 $\frac{3}{4}$ inch casing string 250, hanger-head 251, back-off-joint 252, and riser 253 are installed as in the conventional completion.

There is a slight difference in hanger-head 251 and back-off joint 252. Hanger-head 251 is provided with an internal vertical slot 259 immediately above the hanging recesses 258. Orientation in this method will be obtained by orienting the 10 $\frac{3}{4}$ inch hanger-head 251 rather than the 7 inch hanger-head in the afore-described casing-tubing sub-surface completion. Back-off joint 252 is provided with an orientating bushing 260 which has a double ramp orienting slot 261 cut on a 45° angle. A vertical slot 262 is cut at the bottom of ramp 261 for alignment with hanger head slot 259. A hanger-head and back-off joint equipped with the modifications of hanger-head 251 and back-off joint 252 could be used with the casing-tubing sub-surface completion previously described, providing an option, at this point, of either casing-tubing completion or tubing-less completion.

Blowout prevention equipment 2 is attached at the upper end of riser 253 at the drilling platform. Running of tubing will be performed through this blowout prevention equipment so that full pressure control is maintained at all times as in the previously described method.

In the next step, two strings of tubing 270, 271 are clamped together and run in the well tied by shear pins 273 to a tubing hanger assembly 280. Tubing hanger 280 is provided with outwardly biased hanging latches 281 and inwardly biased tubing latches 282 around openings 284, 285 through which tubing strings 270, 271 pass. An offset opening (not shown) through the hanger 280 provides access to the annulus between the tubing string 270, 271 and 10 $\frac{3}{4}$ inch casing 250. This allows both cementing circulation and limited gas lift production.

Also provided on hanger 280 is an external spring loaded dog 290. Referring also to FIG. 7A dog 290 is beveled at the top 291 and bottom 292 so that it is cammed inwardly by any horizontal shoulder it encounters as the hanger is lowered into the well. However, looking at the face of dog 290, its bottom 292 is V-shaped providing 45° angle edges 293, 294. If these angle edges 293, 294 encounter a matching 45° angle shoulder such as orienting ramp 261, the dog 290 will not be cammed inwardly but will ride down the ramp causing the tubing hanger 280 to rotate therewith. Thus, as the tubing strings 270, 271 and hanger 280 are lowered into the well, dog 290 engages ramp slot 261 rotating the hanger 280 until dog 290 falls through vertical slot 262 and into slot 259 as shown. Latches 281 engage hanging recesses 258 in a proper orientation.

Attached to the upper end of tubing strings 270, 271 are tubing hanging nipples 275, 276 which are provided with external hanging grooves 277, 278. One of the nipples, in this case 275, is longer than the other for reasons to be described subsequently. Running tools 286, 287 connect the hanging nipples 275, 276 to running strings 296, 297.

After the tubing hanger 280 is in place as shown in FIG. 7, the weight of tubing 270, 271 shear pins 273. Both strings 270, 271 are then run to bottom and tubing latches 282 engage the latch grooves 277, 278 in hanging nipples 275, 276, supporting the tubing strings as shown in FIG. 8. Both strings can then be cemented and handling strings 296, 297 and running tools 286, 287 removed by rotation to the right. At this stage of completion the wellhead equipment appears as in FIG. 8.

If for any reason tubing strings 270, 271 should become stuck after tubing hanger 280 is latched in, and cannot be freed, both strings would be cemented in. Then a standard outside tubing cutter would be run over one of the tubing strings. The cutter would be modified slightly to support tubing slips at its bottom. These tubing slips (not shown) would be lowered to engage tapered receiving bowls 288, 289 in the top of the hanger 280. The slips would be set and then the tubing string would be cut off at a distance from hanger 280 equal to the height of hanging nipples 275, 276, one longer than the other. After one tubing is set and cut the same procedure would be followed for the other tubing string.

Next, tubing strings 270, 271 are plugged and risers 253 and 243 are removed by 30° rotational disengagement of breech-block connections 246, 254 as in the casing-tubing sub-surface completion previously discussed. This leaves only the 30° riser 212.

As now shown in FIG. 9, a Christmas tree adapter 300, similar to the adapter 100 (FIGS. 5 and 6), is lowered through riser 212 on drill pipe 320 and combination running and testing tool 330. The external midpor-

tion of adapter 300 is provided with the male part of breech-block connection 301 for engagement with head 251. Rotatably connected by ball bearings 302, at the lower part of adapter 300, is annular packoff assembly 303. Assembly 303 differs from the casing-tubing sub-surface completion apparatus in that it is designed to also packoff around hanging nipples 275, 276 as well as against head 251. The lower retaining ring 304 of packoff assembly 303 is provided with an offset frusto conical surface, the axis of which coincides with the axis of landing nipple 275. Thus, if the packoff assembly is not properly oriented as tubing head adapter 300 is lowered into place, the frusto-conical surface 305 contacts one of the tubing nipples, and is cammed around to the proper orientation. Nipple 275 is longer than nipple 276 to prevent the possibility of both nipples contacting surface 305 at the same time should assembly 300 be exactly ninety degrees out of proper orientation. Packoff assembly 300 also has an annular access port 306.

Running tool 330 seals on the inside diameter of adapter 300 at 307 and on the outside diameter of hanging nipples 275, 276 at 308, 309. Internal porting 310 within the tool 330 permits pressure testing of the packoff assembly 303.

Christmas tree adapter 300 has an upper flange member 311 and internal connection threads 312 to which tool 330 is connected. The adapter 300 also has stop lugs 313 which cooperate with hanger-head stop lugs 314 to limit stop rotation at full engagement as explained with reference to FIG. 5 in the casing-tubing sub-surface completion method previously described herein. Also provided is a lock ring 315 held first in an upward position by sleeve skirt 336 of the tool 330. After shearing of pin 337 right hand rotation of tool 330 allows pins 317 to drop out of L-slots 335 in sleeve 336 allowing its lugs 316 to drop between the back of adapter lugs 313 and the next closest hanger-head lugs 314, locking the adapter in its fully engaged position. Further rotation of tool 330 frees it for retrieval from the well.

The well can then be temporarily abandoned as explained in the casing-tubing sub-surface method previously described or it can be completed for production. If it is to be completed for production, at this point, conductor riser 212 is disconnected from conductor head 211 by 30° rotation and removed.

Now referring to FIG. 10, a spool piece 350, and Christmas tree 360 is guided into place and attached to adapter flange 311 by standard type driver assist clamp 351. Spool piece 350 may be lowered by itself first with Christmas tree 360 being lowered afterward. Alternatively, Christmas tree 360 may be assembled with spool piece 350 by clamp 361, then lowered together into place for attachment to adapter 300. Spool piece 350 is provided with nipples 352, 353 which stab and seal over hanging nipples 275, 276. It is also provided with a side opening outlet 354 and bore 355 communicating with port 306 and tubing-casing annulus below hanger 280 through a port (not shown) in hanger 280. A valve removal plug 356 allows for future installation of a side outlet valve. Christmas tree 360 is provided with short nipples 362, 363 which sealingly engage pockets provided for this purpose in spool piece 350. Nipples 362, 363, 352, 353, 275, 276 and spool bores 357, 358 provide unobstructed full opening into tubing strings 270, 271.

Another alternative for full control completion may be understood with reference to FIGS. 11-14. The early stages of completion are the same as in the previously described methods. A 30 inch casing head 411 supports in succession 16 inch surface casing 440, 10 $\frac{1}{2}$ inch intermediate casing 450 and production casing string 460. Each of these casing strings have a hanger-head 441, 451, 461, back-off joints 442, 452, 462 and risers 443, 453. The riser for production casing 460 has been removed in FIG. 11. There is also a 30 inch conductor riser 413.

In the previous methods described it was necessary to orient the production casing hanger-head prior to installation of the tubing strings. This is rather difficult to do on a deep water well since it requires constant marking and observation of casing riser joints as they are lowered toward the well. However, in the presently described alternate method this requirement is eliminated. After production casing 460 is set, its riser may be removed and replaced by a special tubing head 470 which may be lowered on a tool (not shown), connected by J-slots 471, and attached to hanger-head 461.

Next, orientation apparatus designated generally at 480, is run through riser 453, connected by a J-slot arrangement to a running tool and running string, similar to those shown in FIG. 2 of the previously described method. Like in the foregoing method the orientation apparatus has an outer sleeve 481 and an inner bushing 482 which has a dual 180° ramp 483 and vertical slot 484. However, the method of orienting the orientation apparatus itself is somewhat different.

As more clearly seen in FIG. 12 attached to the lower end of sleeve 481 and bushing 482 is an orientation pin 485. It is attached by shear links 486, screws 487 and shear pins 488. This orientation pin 485 is a sleeve like member which has longitudinal slots 486 cut in its lower end, at 45° intervals in this case, thereabout. Tubing head 470 has corresponding lugs 476 welded around a counterbore 474, near its upper end. As sleeve 481, bushing 482 and orientation pin 485 are lowered into head 470 they are positioned so that the slot 484 is close to its desired orientation. When orientation pin 485 strikes the lugs 476 in head 470 it is rotated, less than 45°, until slots 486 engage tubing head lugs 476. Amount of rotation to engage is noted. Orientation pin 485 has an external annular recess 489 thereabout which is engaged by a snap ring 477 in head 470 when the pin reaches its final resting position on counterbore shoulder 478. Thus, the orientation pin 485 is latched in place so that the slot 484 of bushing 482 is in its proper orientation. Then, the tool (not shown) for installing sleeve 481, bushing 482 and orientation pin 485 is removed.

Referring next to FIG. 13, the tubing hanger 500 and attached tubing strings 501, 502 are then run in the well on tubing hanger running tool 550 and handling strings 551, 552. Tool 550 has an orientation key 555 on one side which can be adjusted by rotating it about the tool body, the amount previously noted for engagement of the orientation pin 485. Key 555 has a V- or wedge-shaped leading edge 556. When the key edge 556 contacts ramp 483 (see FIG. 11) it rotates tool 550 until key 555 fully engages orientation bushing slot 484. Thus, the tubing hanger 500 and tubing strings 501, 502 are properly and exactly oriented as they approach a resting place.

Handling strings 551, 552 are connected to their respective strings 501, 502 with reference to string 501 only, by a handling nipple 511 and a landing nipple 521 which slidably engage the vertical bore 531 of hanger 500. Surrounding the lower end of landing nipple 521 and its counterpart 522 for the other string 502 is a tubing hanger latch mechanism which includes a lower plate 560 connected to an upper plate 561 by a plurality of shear bolts 562. These plates 560, 561 slidably engage a counterbore 545 in the lower end of hanger 500. In the original lowering position the bottom 546 of counterbore 545 rests directly at upper plate 561 and is temporarily held there by shear pins 557 which engage holes 558 in lower plate 560. In such a position lateral latch members 565 are retracted in latch windows 568 and lie partially in latch recesses 566.

As the strings are lowered into place the bottom of tubing hanger 500 first contacts and comes to a stop against the support shoulder 474 in tubing head 470. The weight of strings 501, 502 then shear shear pins 557 allowing plates 561, 562 and landing nipples 521, 522 to move downward to the position shown in FIG. 13, coming to a rest when landing nipples 521, 522 engage support shoulders such as 548 in tubing hanger 500. During this moving down latch members 565 are cammed outwardly of windows 568 into engagement with latch groove 475 of head 470 by the cam surface 569 of latch recess 566. This position is maintained by the engagement of a snap ring 570, carried by lower plate 560, with an annular recess 553 in the lower end of hanger 500. Thus, tubing hanger 500 and string 501, 502 are latched in place.

If it were necessary to remove the tubing hanger 500 and tubing strings 501, 502 at this or a later time an upward pull would be exerted on landing nipples 521, 522 and thrust collars 523, 524 thereabout until shear bolts 562 were broken. This would allow upper plate 561 to move upwardly against tubing hanger counterbore bottom 546 so that latch members 565 could be retracted by the camming action between cam surface 565_a and latch groove cam surface 475_a. With latch members 565 retracted, tubing hanger 500 and strings 501, 502 would be free for removal. The lower plate 560 would be carried upward on the shoulders of tubing couplings on strings 501 and 502.

Under normal circumstances, however, the tubing hanger 500 and tubing string 501, 502 would remain in the latched condition shown in FIG. 13 while handling nipples 511, 512 and tubing hanger running tool 550 were removed. However, prior to the removal of running strings 551, 552 and tool 550, tubing plugs would be installed in the latch recesses 525 of landing nipple 521, 522 placing the tubing strings 501, 502 under pressure control. The removal of handling nipples 511, 512 and tool 550 is accomplished simply by rotating running strings 551, 552 in a direction so that the threaded connection 515 between landing nipples 521, 522 and handling nipples 511, 512 is disengaged. The major diameter of handling nipple 511 is greater than the passageways 559 through tool 550. Therefore, the shoulder 519 would cause the tool 550 to move upwardly with the handling strings 551, 552.

At this point the orientation sleeve 481 and bushing 482 are removed by the same type of J-slot tool with which it was installed. However, since the orientation pin 485 is locked in place by snap ring 477 it is necessary to pull upwardly with enough force to shear pin

488. Thus, the orientation pin 485 is left in place for subsequent orientation in workover operations or the like. It is a simple matter to reinstall the orientation sleeve 481 and bushing 482 by reengaging the orientation pin 485 in the recess on the bottom of bushing 482.

After the tubing strings 501, 502 have been installed and orientation sleeve 481 and bushing 482 have been removed, the surrounding risers 453, 443 and possibly 413 are removed in order. The conductor riser 413 may be cut off near the tubing head 470 to provide a means for attaching a guide base as will be more fully understood with reference now to FIG. 14.

After the risers have been removed a wellhead 455, attached to a casing joint 456, and backoff joint, similar to 452 in FIG. 11, may be connected to hanger-head 451. Attached to the outside of wellhead 455 may be a support or guide base 600 which may be welded to conductor riser 413. Guide base 600 may provide support for guide means 601 and various other support functions such as flowline connections and the like.

After installation of wellhead 455 a packoff member 610 may be placed in the annular space between tubing head 470 and wellhead 455. Packoff member 610 may be similar to those shown in copending U. S. Patent application Ser. No. 783,943 and may be installed in a similar manner.

In the final steps a production assembly, commonly referred to as a Christmas tree 620, is guided into place and attached to wellhead 455 by a clamp 630, if assisted by divers, or with a remote connector (not shown). Christmas tree 620 is provided with tubing nipples 621, the other nipple not shown, and annular access nipple 623. Although it has not been previously mentioned, tubing hanger 500 may also have an annular access port (not shown) which allows access to the area surrounding tubing strings 501, 502. This port provides communication between annular access nipple 623 and nipple extension 624.

The foregoing methods and apparatus for completing an underwater well for both the casing-tubing sub-sea completion or tubingless completion offer definite advantages in both speed and safety. Complete pressure control at the drilling platform is maintained at all times and the apparatus used permits fast connection and disconnection for reduction of expensive rig time.

Various embodiments of the invention are shown in the drawing and described in the specification, but many variations thereof will be apparent to those skilled in the art. It is not practical to show or describe all the variations included within the invention, and therefore the embodiments described should be considered illustrative only, and not limiting, the scope of the invention being as broad as is defined by the appended claims. The form of the claims and the specification, including the Abstract, is adopted solely for easier reading and understanding, and should not be considered in interpreting the scope of the invention claimed.

I claim:

1. A method of completing an underwater well comprising the steps of:
locating drilling means at an underwater well site;
installing conductor casing in the floor of a body of water with a casing head and riser attached thereto at a point near said floor, said riser extending upwardly to said drilling means;
drilling holes for, suspending within said conductor casing and cementing in place other casing, each of

said other casing being suspended near said floor by hanger means above which other risers, extending upwardly to said drilling means are connected; attaching blowout pressure control equipment to the top of at least one of said other risers at said drilling means prior to removal of any of said other risers; removing through said pressure control equipment any of said other risers which are surrounded by the riser to which said pressure control equipment is attached;

running a tubing head means through said pressure control equipment and said riser to which it is attached;

running a tubing hanger and at least one tubing string, through said control equipment and the riser to which it is attached, into the innermost casing; suspending and latching said tubing hanger and tubing string in said tubing head means; and

removing said pressure control equipment and the remainder of said other risers.

2. A method of completing an underwater well as set forth in claim 1, characterized in that prior to running said tubing-hanger means, first orientation means is run through said pressure control equipment, and said riser to which it is attached, and is latched to said tubing head means, said tubing hanger being provided with second orientation means engageable with said first orientation means on said running of said tubing hanger to automatically align said tubing hanger and tubing string in a predetermined orientation.

3. A method of completing an underwater well as set forth in claim 2, characterized in that prior to said removing of said pressure control equipment, at least a portion of said first orientation means is removed and after said removing of said pressure control equipment and said other risers an underwater wellhead is attached to said well around said tubing head and said tubing hanger.

4. A method of completing an underwater well as set forth in claim 3, characterized by the further steps of: packing off an annular space between said tubing head and said wellhead and attaching a Christmas tree to said wellhead.

5. A method of completing an underwater well as set forth in claim 1, characterized by the further steps of: attaching a wellhead to one of said hanger means with an annular space between said wellhead and said tubing head; packing off said annular space; and attaching a 50 Christmas tree to said wellhead.

6. Underwater well completion apparatus comprising:

a first casing string penetrating the floor of a body of water;

first hanger-head means connected to the upper end of said first casing string near the floor of said body of water;

riser means connected to said first hanger-head means extending upwardly through said body of water to the surface of said body of water;

pressure control means connected to the upper end of said riser means;

a second casing string, lowerable through said pressure control means and said riser means, supported by second hanger-head means on said first hanger-head means;

tubing head means lowerable through said pressure control means and said riser means and connected to said second hanger-head means;

tubing hanger means lowerable through said pressure control means and said riser means to a position within said tubing head means to be supported thereby; and

at least one tubing string supported by said tubing hanger means and lowerable through said pressure control means and said riser means.

7. Underwater well completion apparatus as set forth in claim 6 characterized by first orientation means lowerable through said pressure control means and said riser means connected to said tubing head means and 15 second orientation means on said tubing hanger means to position said tubing hanger means within said tubing head means in a predetermined angular orientation relative thereto.

8. Underwater well completion apparatus as set forth in claim 7 characterized in that said first orientation means comprises a helically generated upwardly facing surface.

9. Underwater well completion apparatus as set forth in claim 7 characterized in that said riser means and at least a portion of said first orientation means are removable and reengageable with said tubing head means to permit subsequent removal and replacement of said tubing hanger means in the same said predetermined angular orientation.

10. Underwater well completion apparatus as set forth in claim 6 characterized in that said tubing hanger means is provided with remotely actuatable latch means to lock said tubing hanger means to said tubing head means.

11. Underwater well completion apparatus comprising:

conductor casing means penetrating the floor of a body of water;

casing head means affixed to said conductor casing means near said floor;

other casing means concentrically disposed within said conductor casing means;

hanger means connected to said other casing means, said hanger means being provided with support means engageable with other support means surrounding said hanger means to limit longitudinal movement of said other casing means and said other hanger means;

riser means connected to at least one of said hanger-head means extending upwardly therefrom to drilling means above the surface of said body of water; pressure control means connected to the upper end of at least one of said riser means;

tubing head means lowerable through said pressure control means and the riser means to which it is attached and connected to the innermost of said hanger means;

tubing hanger means lowerable through said pressure control means and said riser means to a supported position within said tubing head means;

at least one tubing string connected to said tubing hanger means and lowerable therewith through said pressure control means and said riser means to said supported position; and

characterized in that said tubing hanger means is provided with latch means engageable with said tubing head means on longitudinal movement of said

string relative to said tubing hanger means to said tubing head means.

12. Underwater well completion apparatus as set forth in claim 11 characterized by first orientation means lowerable through said pressure control means and connected to said tubing head means and second orientation means on said tubing hanger means cooperative with each other to automatically orient said tubing hanger means in a predetermined angular position relative to said tubing head means.

13. Underwater well completion apparatus as set forth in claim 12, characterized in that said first orientation means comprises an upwardly facing helical surface terminating at a longitudinal slot means and said second orientation means comprises key means engageable with said helical surface and slidable thereon to rotate said tubing hanger means to allow said key means to engage said slot means.

14. Underwater well completion apparatus as set forth in claim 12 characterized in that at least a portion of said first orientation means is removable from said tubing head and subsequently reengageable therewith in the same orientation as before removable.

15. Underwater well completion apparatus comprising:

conductor casing means penetrating the floor of a body of water;
casing head means attached to said conductor casing means near said floor;
other casing means concentrically disposed with said conductor casing means;
hanger means connected to said other casing means, said hanger means being provided with support means engageable with other support means surrounding said hanger means to limit longitudinal movement of said other casing means and said other hanger means;
tubing head means connected above said hanger means in internal fluid flow communication with the innermost of said other casing means and having a maximum diameter no greater than the inside diameter of the casing means adjacent said innermost casing means;
tubing hanger means supported on said tubing head means;

at least one tubing string supported by said tubing hanger means;
tubular wellhead means connected to one of said hanger means above and in communication with said adjacent casing means, an annular space being left between said wellhead and said tubing head; a Christmas tree assembly connected above said wellhead means, said Christmas tree assembly being provided with at least one flow bore; and a nipple means between said tubing hanger means and said Christmas tree assembly providing fluidtight flow communication between said tubing string and said Christmas tree assembly flow bore.

16. Underwater well completion apparatus as set forth in claim 15, characterized by packoff means installed in said annular space to prevent fluid passage therethrough.

17. Underwater well completion apparatus as set forth in claim 15, characterized in that said tubing head means and said tubing hanger means are provided with orientation means for positioning said tubing hanger

means within said tubing head means in a predetermined angular orientation relative thereto.

18. A method of completing an underwater well comprising the steps of:

- 5 locating drilling means at an underwater well site; installing conductor casing in the floor of a body of water with a casing hanger and riser attached thereto at a point near said floor, said riser extending upwardly to said drilling means;
- 10 drilling holes for, suspending within said conductor casing and cementing in place other casing, each of said other casing being suspended near said floor by hanger head means above which other risers, extending upwardly to said drilling means are connected;
- 15 attaching blowout pressure control equipment to the top of at least one of said other risers at said drilling means prior to removal of any of said other risers; installing an innermost casing hanger suspending an innermost string of casing from the hanger head means of the previously installed casing;
- 20 removing through said pressure control equipment any risers which are surrounded by the riser to which said pressure control equipment is attached; running a tubing head into the well;
- 25 attaching said tubing head to said innermost casing hanger;
- 30 running a tubing hanger and at least one tubing string, through said pressure control equipment and the riser to which it is attached, into the innermost string of casing;
- 35 suspending and latching said tubing hanger and tubing string in said tubing head; and
- 40 removing said pressure control equipment and the remainder of said other risers.

19. A method of completing an underwater well as set forth in claim 18, characterized in that prior to running said tubing hanger the method further comprises

- 45 the steps of:
lowering a orientation means through said pressure control equipment and said riser to which it is attached; and
latching said orientation means to said tubing head, said tubing hanger being provided with means engageable with said orientation means on said running of said tubing hanger to align said tubing hanger and tubing string in a predetermined orientation.
- 50 20. A method of completing an underwater well as set forth in claim 19, characterized in that prior to removing said pressure control equipment, the method further comprises the steps of:
removing the alignment means of said orientation means; and
after removing said pressure control equipment, attaching an adapter to said well around said tubing head and said tubing hanger.

- 55 21. A method of completing an underwater well as set forth in claim 20, characterized by the further steps of:

packing off an annular space between said tubing head and said adapter; and
attaching a Christmas tree to said adapter.

- 60 22. A method of completing an underwater well as set forth in claim 18, characterized by the further steps of:

- attaching an adapter to one of said hanger head means with an annular space between said adapter and said tubing head;
packing off said annular space; and
attaching a Christmas tree to said adapter. 5
23. Underwater well completion apparatus comprising:
a first casing string penetrating the floor of a body of water;
hanger head means connected to the upper end of 10 said first casing string near the floor of said body of water;
riser means connected to said hanger head means extending upwardly through said body of water to the surface of said body of water; 15
pressure control means connected to the upper end of said riser means;
a second casing string lowerable through said pressure control means and said riser means;
casing hanger means supporting said second casing 20 string on said hanger head means;
tubing head means lowerable through said pressure control means and said riser means;
connecting said tubing head means to said casing 25 hanger means;
tubing hanger means lowerable through said pressure control means and said riser means to a position within said tubing head means to be supported thereby; and
at least one tubing string supported by said tubing 30 hanger means and lowerable through said pressure control means and said riser means.
24. Underwater well completion apparatus as set forth in claim 23 further comprising:
orientation means lowerable through said pressure control means and said riser means for connection to said tubing head means; and
said tubing hanger means including means for engaging said orientation means for positioning said tubing hanger means within said tubing head means at a predetermined angular orientation relative thereto. 40
25. Underwater well completion apparatus as set forth in claim 24 wherein said orientation means includes a helically generated upwardly facing surface. 45
26. Underwater well completion apparatus as set forth in claim 24 wherein said riser means and at least a portion of said orientation means are removable and re-engageable with said tubing head means to permit subsequent removal and replacement of said tubing hanger means in the same said predetermined angular orientation. 50
27. Underwater well completion apparatus as set forth in claim 23 wherein said tubing hanger means is provided with remotely actuatable latch means to lock said tubing hanger means to said tubing head means. 55
28. Underwater well completion apparatus comprising:
conductor casing means penetrating the floor of a body of water;
casing head means affixed to said conductor casing means near said floor;
other casing means concentrically disposed within 60 said conductor casing means;
hanger head means connected to said other casing means, said hanger head means being provided

- with support means engageable with other support means surrounding said hanger head means, to limit longitudinal movement of said other casing means and said other hanger head means;
riser means connected to at least one of said hanger head means extending upwardly therefrom to drilling means above the surface of said body of water;
pressure control means connected to the upper end of at least one of said riser means;
casing hanger means suspending a string of casing lowerable through said pressure control means and the riser means to which it is attached and supported by the innermost of said hanger head means;
tubing head means lowerable through said pressure control means and the riser means to which it is attached for connection to said casing hanger means;
tubing hanger means lowerable through said pressure control means and said riser means to a supported position within said tubing head means;
at least one tubing string connected to said tubing hanger means and lowerable therewith through said said pressure control means and said riser means to said supported position; and
characterized in that said tubing hanger means is provided with latch means engageable with said tubing head means on longitudinal movement of said tubing string relative to said tubing hanger means. 30
29. Underwater well completion apparatus as set forth in claim 28 further comprising:
orientation means lowerable through said pressure control means and said riser means for connection to said tubing head means; and
said tubing hanger means including means for engaging said orientation means for positioning said tubing hanger means within said tubing head means at a predetermined angular orientation relative thereto. 40
30. Underwater well completion apparatus as set forth in claim 29, wherein said orientation means includes an upwardly facing helical surface terminating at a longitudinal slot and said engaging means including key means engageable with said helical surface and slideable thereon to rotate said tubing hanger means to allow said key means to engage said slot means. 45
31. Underwater well completion apparatus as set forth in claim 29 wherein at least a portion of said orientation means is removable from said tubing head means and subsequently re-engageable therewith in the same previous orientation. 50
32. Underwater well completion apparatus comprising:
conductor casing means penetrating the floor of a body of water;
casing head means attached to said conductor casing means near said floor;
other casing means concentrically disposed within 55 said conductor casing means;
hanger head means connected to said other casing means, said hanger head means being provided with support means engageable with other support means surrounding said hanger head means, to limit longitudinal movement of said other casing means and said other hanger head means;
casing hanger means suspending a string of casing from said innermost hanger head means;

tubing head means connected above said casing
hanger means in communication with said casing
suspended by said casing hanger means and having
a maximum diameter no greater than the inside di-
ameter of the innermost casing means; 5
tubing hanger means supported on said tubing head
means;
at least one tubing string supported by said tubing
hanger means;
adapter means connected to one of said hanger head 10
means above and in communication with said in-
nermost casing means, an annular sac being left
between said adapter and said tubing head means;
a Christmas tree assembly connected above said
adapter means, said Christmas tree assembly being 15
provided with at least one flow bore; and
nipple means between said tubing hanger means and
said Christmas tree assembly providing fluid type
flow communication between said tubing string
and said Christmas tree assembly flow bore.

33. Underwater well completion apparatus as set
forth in claim 32, further comprising packoff means in-
stalled in said annular space to prevent fluid passage
therethrough.

34. Underwater well completion apparatus as set 25
forth in claim 32, wherein said tubing head means and
said tubing hanger means are provided with orientation
means for positioning said tubing hanger means within
said tubing head means in a predetermined angular ori-
entation relative thereto. 30

35. An apparatus for orienting a tubing hanger within
a well, comprising:
a support aligned and affixed within such well;
orientation means for aligning such tubing hanger in 35
a predetermined orientation;
said support having guide means to properly align
said orientation means within such well; and
said orientation means including alignment means for
aligning such tubing hanger within such well, con-
nection means for connecting said orientation 40
means and said support, and release means for dis-
connecting said alignment means from said con-
nection means.

36. An apparatus as defined in claim 35 wherein said 45
orientation means further includes re-engagement
means for re-engaging said alignment means and said
connection means in said predetermined orientation
within the well.

37. An apparatus as defined in claim 35 wherein said
alignment means includes 50
a bushing having a dual 180° ramp at its upper end
and a vertical slot communicating with the ramp at
its lowermost intersection for engagement with a
key mounted to such tubing hanger whereby the
key contacts said ramp and rotates such tubing 55
hanger until such key fully engages said vertical
slot.

38. An apparatus as defined by claim 37 wherein:
said connection means includes a sleeve having a plu-
rality of recesses on its lower end; and
said support including a cylinder mounted within 60
such well with said guide means including a plural-
ity of lugs affixed to the upper end of said cylinder
for engagement with said recesses whereby said
orientation means is predeterminedly aligned with
said support. 65

39. An apparatus as defined by claim 38 wherein:

said connection means includes a snap ring retract-
ably installed in an annular recess in the internal
surface of the upper end of said cylinder for re-
tracting into a mating annular recess in the external
surface of said sleeve upon alignment of the reces-
ses.

40. An apparatus as defined by claim 39 wherein
said release means includes shear links connecting
said bushing and said sleeve whereby an upward
force on said bushing causes said links to break dis-
connecting said alignment means from said con-
nection means.

41. An apparatus as defined by claim 40 wherein
said bushing has a plurality of notches engageable
with a plurality of pins on the upper end of said
sleeve whereby said alignment means may be re-
engaged with said connection means after release
with said alignment means in said predetermined
orientation.

42. A tubing hanger for suspending a string of tubing
from a tubing head within a well comprising:
a cylindrical body having a vertical bore and a coun-
terbore;

a nipple reciprocably mounted within said bore and
adapted for connection with such string of tubing;
a plug reciprocably mounted within said counterbore
having an upper plate and a lower plate; said plug
being held against the bottom of said counterbore
by a shear pin; said upper plate having an annular
latch groove in its periphery in which an expand-
able latch is mounted; said lower plate having an
annular recess in its periphery in which a snap ring
is mounted; and

said nipple being affixed to said upper plate whereby
upon landing said tubing hanger said nipple continues
moving downwardly shearing said shear pin
thereby causing said plug to move downward in
said counterbore until said latch expands into an
annular recess in the internal surface of such tubing
head and said snap ring engages an annular groove
in the internal surface of such tubing head thereby
connecting said tubing hanger to said tubing head.

43. A tubing hanger as defined by claim 42 wherein
said upper plate and said lower plate are connected
by shear bolts whereby upon moving said nipple
upward said bolts break causing said upper plate to
engage the bottom of the counterbore leaving the
lower plate in position due to said snap ring thereby
permitting said latch to retract into said recess in
said upper plate and said tubing hanger to be re-
moved from the well.

44. An apparatus for completing a well where the
well includes an outer casing supported in the ground
and a casing hanger mounted within the outer casing,
comprising:

a tubing head mounted on such casing hanger;
a tubing hanger suspending a string of tubing from
said tubing head;
an adapter for connection with a Christmas tree; said
adapter being connected to such outer casing; and
a packoff member mounted within said adapter and
around a portion of said tubing head for sealingly
engaging the external surface of said tubing head
and the internal surface of said adapter.

45. An apparatus as defined in claim 44 wherein said
packoff member includes:
an upper ring;

21

a lower ring; and
a seal sandwiched between said upper and said lower
ring; said seal being compressed into sealing en-
gagement with said external surface of said tubing

22
head and said internal surface of said adapter as
said lower ring engages an annular restrictive
shoulder in said adapter.
